(No Model.)

F. J. CODDINGTON & M. POPP.

SAFETY GATE FOR BRIDGES.

No. 388,833.

Patented Sept. 4, 1888.

UNITED STATES PATENT OFFICE.

FRANK J. CODDINGTON AND MICHAEL POPP, OF CHICAGO, ILLINOIS.

SAFETY-GATE FOR BRIDGES.

SPECIFICATION forming part of Letters Patent No. 388,833, dated September 4, 1888.

Application filed January 9, 1888. Serial No. 260,244. (No model.)

To all whom it may concern:

Be it known that we, FRANK J. CODDINGTON and MICHAEL POPP, citizens of the United States, residing at Chicago, in the county of Cook and State of Illinois, have invented a certain new and useful Improvement in Safety-Gates for Bridges, which is fully set forth in the following specification, reference being had to the accompanying drawings, in which—

10 Figure 1 represents a face view of an abutment of a bridge having our improved safety-gate applied thereto, the same being shown partly in section; Fig. 2, a side elevation of a bridge having our safety-gate applied thereto, the abutment being shown in section; Fig. 3, a detail view of the screw-shaft with its pinion and traveler detached, the latter being shown in section; Fig. 4, an end elevation of the bridge-draw; and Fig. 5, a detail view of one-half of the traveler, showing the inner face thereof and the fork in position.

15 Like letters refer to like parts in all the figures of the drawings.

Our invention relates to safety-gates for bridges, and more particularly for that class of bridges known as "swing" or "draw" bridges, in which the bridge proper revolves upon a central pivot.

20 The object of our invention is to provide a gate for each abutment of bridges of this description, which gate shall close the roadway leading along the abutment to the bridge when the bridge is not in line with the abutments, or, in other words, is open, and which 25 will open so as to leave the roadway clear when the bridge is in line with the abutments, or closed, the necessary movements to effect these results being automatic in their nature and being caused by the swinging of the bridge.

30 We will proceed to describe a construction in which we have practically carried out our invention in one form, and will then particularly point out in the claims those features which we deem to be new and desire to protect by Letters Patent.

35 In the drawings, A represents the bridge proper, mounted to swing on a central pivot, A'; and B, one of the abutments thereof, it being understood, of course, that a similar abutment is arranged at the other end of the bridge. The abutment B is provided with a chamber

or recess, B', within which the working parts of the apparatus are arranged, said chamber being covered by the roadway B².

C represents the gate, which moves vertically in suitable ways, and which, when open, is sunk within the chamber B', as shown in Fig. 2, so that its top is level with the roadway B². The roadway is provided with a slot, b, for the passage of the gate, and at each end 60 of the said slot there is arranged a standard or upright, D, preferably constructed in the form of a hollow pillar, as shown in the drawings. Each pillar D serves to support a pulley-wheel, d, and there is attached to each end 65 of the gate C a rope or cable, D', which passes over the corresponding pulley-wheel, d, and is provided with a counterpoise-weight, d', arranged within the pillar D. The weights d' serve to counterbalance the weight of the gate 70 C, so that the said gate may be moved freely either up or down with very little power.

E represents a screw-shaft mounted in suitable bearings in the abutment B and arranged in a vertical position. This screw-shaft is provided with a double thread, e, one portion of which is right-handed and the other portion left-handed, and the ends of the two threads being connected, as shown, so as to form a single continuous thread or groove.

80 F indicates a traveler mounted on the screw-shaft E and moving vertically thereon, said traveler being provided with a central aperture, f, corresponding in diameter to the shaft E. The traveler F is provided with a fork, 85 F', journaled therein and fitting the thread e. The construction of these parts which we prefer is that shown in the drawings, in which the traveler F is constructed in two similar halves divided horizontally, one-half of the 90 bearing of the shank f' of the fork F' being formed in each half and the two halves being connected by screw-bolts f'.

F² represents an arm, one end of which is secured to the traveler F, while the other end 95 is secured to the gate C.

F³ represents a gear-wheel secured on the upper end of the shaft E and serving to actuate the same.

On each end of the bridge proper, A, there is secured a rack, G, which may of course mesh directly with the gear-wheel F³; but in prac-

tice we prefer to employ an intermediate gear-wheel, G' , which meshes with the gear-wheel F^3 , and also with the rack G .

The operation of the apparatus is as follows:

- 5 When the bridge is closed, or, in other words, in line with the abutments, the various parts are in the position shown in the drawings and the gate C is below the level of the roadway, leaving this latter open for traffic. Upon 10 turning the bridge in either direction the shaft E will be rotated and the traveler F will move upward thereon, owing to the engagement of its fork F' with the thread e on said shaft. By the time the bridge has left the abutment the 15 gate C will be raised to its highest position, as shown in dotted lines in Fig. 1 of the drawings, and will remain in that position until the bridge is again closed. This upward movement of the gate begins at the moment that 20 the bridge begins to move, and is completed by the time that the end of the rack G leaves the gear-wheel G' , or, in other words, before the bridge is half open, thus insuring a greatly-increased immunity from accident. When 25 the bridge is again closed, the rack G will engage with the gear-wheel G' , and will rotate the shaft E through the medium of the gear-wheel F^3 , thereby moving the traveler F downward to the position shown in full lines in the 30 drawings, the traveler carrying the gate downward with it, and thus opening the roadway to traffic.

It will be observed that the gate will operate no matter in which direction the bridge is 35 turned, and will always be closed when the bridge is open and open when the bridge is closed. Moreover, this operation takes place whether the bridge be turned end for end, or whether it be turned ninety degrees and then 40 back to its original position. This feature is of great advantage in bridges employed where there is heavy traffic and where the bridge is liable to be turned in either direction, and also to be turned either completely around or only 45 given a quarter-turn and then turned back.

It is obvious that various modifications in the details of construction may be made without departing from the principle of our invention. For instance, as hereinbefore stated, the intermediate gear-wheel, G' , may be dispensed with, as may also the counter-weights d' . Moreover, instead of employing a single screw-shaft, E , two or more may be employed to operate each gate, if deemed necessary or desirable. Various other modifications will 55 readily suggest themselves, and we therefore do not wish to be understood as limiting ourselves strictly to the precise details hereinbefore described, and shown in the drawings.

Having thus described our invention, what 60 we claim as new, and desire to secure by Letters Patent, is—

1. In a safety-gate for bridges, the combination, with the abutment and the gate proper arranged to slide vertically therein, of the 65 screw-shaft provided with a double thread, a traveler mounted on said shaft and connected to the gate, a gear-wheel on the screw-shaft, and a rack mounted on each end of the bridge proper to operate the said gear-wheel, sub- 70 substantially as and for the purposes specified.

2. In a safety-gate for bridges, the combination, with the bridge A , pivoted centrally at A' and provided with a rack, G , at each end, of the abutments B , each provided with 75 a vertical screw-shaft, E , threaded, as described, and connected to the racks by suitable gearing, a traveler on said screw-shaft, and a vertically-moving gate connected to the traveler and adapted to be projected upward through so a slot in the roadway of the abutment, substantially as and for the purposes specified.

FRANK J. CODDINGTON.
MICHAEL POPP.
